UNITED STATES PATENT OFFICE.

BERNHARD ALEXANDER SMITH, OF MELBOURNE, VICTORIA.

APPARATUS FOR COOLING AND REFRIGERATING.

SPECIFICATION forming part of Letters Patent No. 596,386, dated December 28, 1897.

Application filed June 17, 1895. Serial No. 553,122. (No model.) Patented in England June 11, 1895, No. 11,373.

To all whom it may concern:

Be it known that I, BERNHARD ALEXANDER SMITH, a subject of the Queen of Great Britain, and a resident of Collins Street, Melbourne, in the Colony of Victoria, have invented a certain new and useful Improved Apparatus for Cooling and Refrigerating, (for which I have obtained a patent in Great Britain, No. 11,373, dated June 11, 1895,) of which

10 the following is a specification.

This invention has been devised to provide improvements in the method or process of cooling and refrigerating any fluid medium, such as air or suitable liquids, for the preservation of perishable produce and in general for cooling and refrigerating for other requirements.

The invention is based upon the fact that atmospheric air when compressed and then cooled will, upon such air being made to perform mechanical work during its expansion, have its temperature lowered, and will consequently lower the temperature of bodies in contact with it, owing to the absorption by 25 such expanded air of heat from bodies in its particular locality.

In order that my invention may be the more easily understood, reference may be made to the accompanying drawing, consisting of a 30 plan view, partly in section, of a two-step plant embodying my improvements, and in which—

A is a stop-valve of any approved design, and B an air-inlet valve set within the pipe 35 B', leading into a double-action air-compression cylinder C.

D is a tube or pipe leading from the compression-cylinder C into a horizontal surface condenser E. This condenser E is preferably 40 constructed of longitudinal horizontal tubes, as E', secured into the end plates E² and inclosed in a sealed cell or chamber of staunch construction. From this condenser E a return pipe or duct F is led to another high-pressure double-action compression-cylinder G, from whence another lead-away pipe H 45 proceeds to and enters the end of another cylindrical horizontal surface condenser K. This latter is preferably similar in construction to the condenser E, hereinbefore described.

E³ is a tank or cistern in which the con-

densers E and K are submerged. This tank or cistern is kept filled with water for the purpose of cooling the condensers E K. In this 55 tank or cistern E³ and through the condensers E and K the circulation of the water is maintained by a pump p or analogous mechanism, drawing the liquid preferably from the lower and injecting it into the upper portion of such 60 tank. L is another return pipe or duct joining K with a double-acting expansion-cylinder M.

The cylinders M and G are placed in line and provided with a through piston-rod M', 65 connecting them direct with the steam-engine G', and on this piston-rod are mounted pistons of any suitable design.

N is a lead-away pipe from the aforesaid expansion-cylinder M to a horizontal cylindrical refrigerator O. This latter is similarly 70 constructed to the condensers E and K, hereinbefore referred to.

P is a return tube or duct leading back to another double action expansion-cylinder Q. 75 This cylinder Q is similar in its construction and working to the cylinder M, before described, and its piston-rod Q' likewise proceeds through the cylinder C and steam-cylinder of engine C'.

R is also a lead-away tube connecting the cylinder Q with the refrigerator S, while T is the terminal return-tube leading toward the cylinder C, first hereinbefore described, and in and to the latter portion of which are set 85 the cock A, air-valve B, and final connecting-pipe B'.

U' U² U³ U⁴ are appliances, such as fans or blowers, for circulating the air used as a refrigerating medium through the tubes of the 90 condensers O S in such a manner that such refrigerating medium, when chilled, will uniformly and efficiently circulate around or through the produce rooms or chambers V, preferably in the direction shown by the arrows.

V V are chambers constructed of any approved material, in which the produce or other matters requiring cooling or refrigeration are placed, and although I have shown an open 100 air-passage between such said chambers V V and the outer walls W W, I would have it distinctly understood that I do not confine myself to any arbitrary adherence to such ar-

rangement—as, for instance, I may in some cases cause main-trunk tubes to convey the refrigerating medium through the building, and from such main trunk I may lead branch 5 pipes provided with shutters, stop-cocks, or the like for turning on and off the supply of such refrigerating medium in accordance with requirements at the discretion of the operator.

10 With reference to the steam-engine cylinders C' and G', I would have it distinctly understood that while preferring the piston-rods M' and Q' to proceed through the cylinders placed in line therewith I may alternatively 15 employ other operating-gear—such as a pulley-shaft, for instance, on which may be mounted cranks with connecting-rods—in lieu of the direct motion of the steam-pistons, and, further, expansion - cylinders may be connected by any suitable gear from a shaft in 20 connection with the compression-cylinders.

The *modus operandi* of my invention may be described as follows: Referring to the drawing herewith of a two-step plant, the 25 same has been designed to pump up three million heat-units per day (pound degree centigrade) from a refrigerator at a temperature of 14° centigrade (260° absolute) to a source—viz., the tank of cooling-water E³—at a temperature of 21° centigrade, (295° absolute.) 30 I am presuming that a tank of cooling-water be employed in connection with the condensers E K; but in the case of plants on board ship the source referred to is the sea-water at 35 the depth at which it is drawn into the circulating-pumps, hereinbefore referred to.

To charge the plant with air, the stop-valve A is closed and the air-inlet valve at B is opened. If thought necessary or desirable, 40 the air may be dried by any approved apparatus, such as asbestos soaked in sulfuric acid, on its way to the inlet-valve B. Steam is turned on in the cylinders C' and G' and the plant set working and continued at work till 45 the gage-pressure on the condenser side of the stop-valve A has reached the initial pressure at which the plant is required to work—about forty pounds per square inch absolute.

When the plant has been charged with air 50 up to the initial pressure, the inlet-valve B is closed, the stop-valve A opened, and the engines C' G' work at the required speed to maintain the temperature necessary. When the temperatures at the various parts of the 55 cycle have reached their working values, the temperature of the air just before entering the first compression-cylinder C is a little below the temperature of the refrigerating-room—namely, 252° absolute, as against a 60 temperature of 260° absolute in the refrigerating-room. The air is compressed in the cylinder C till it reaches a pressure of about eighty-seven pounds per square inch absolute and a temperature of 315° absolute, when the 65 outlet-valves open and the air is forced out of the low-pressure compressor C through the exhaust-pipe D into the surface condenser E.

The air is then cooled to a temperature of about 299° absolute by means of the water circulating through the tubes E' in the condenser E while on its passage to pipe F. The air thus cooled passes thence through the pipe F and is admitted to the second compressor G through suitable inlet-valves. It is there compressed to a higher pressure, in this case 75 amounting to one hundred and four pounds per square inch absolute and a temperature of 315° absolute. Thence it passes through pipe H to the second surface condenser K, where again the circulation of water through the 80 pipes E' in the condenser K cools the air to a temperature of about 299° absolute during its passage from pipe H to pipe L. The air, thus having been cooled after each compression, is reduced down to a temperature nearly equal 85 to that of the cooling-water, which is supposed to be at a temperature of 295° absolute. From the pipe L the compressed air at a pressure of one hundred and four pounds per square inch absolute is passed into the first expanding-cylinder M, where it expands till its pressure falls to forty-eight pounds per square inch absolute, the expansion being regulated by suitable expansion-valves and the exhaust taking place through separate valves. During the expansion in the cylinder M the air does work in assisting to compress the air in cylinders G and C, and during this practically adiabatic expansion the working air becomes cooled to a temperature depending on the initial pressure and temperature, and the amount of expansion is so regulated that the air is cooled to a temperature a little lower than that of the refrigerating-room, say to a temperature of 36° centigrade or 238° absolute. The 90 air then passes by the pipe N to the surface condenser O.

The air of the refrigerating - chamber is driven and delivered by blowers U' U² through the tubes in the surface condenser O. The 110 temperature of the working air on its passage through the condenser O to pipe P is thus raised nearly to that of the refrigerating-room, say from a temperature of 238° absolute to a temperature of 252° absolute. The 115 air is drawn off through the pipe P to the second expanding - cylinder Q, where it is again allowed to expand till its pressure falls to about forty pounds per square inch absolute and work in assisting to drive the 120 compressors C and G, the expansion being regulated by means of any approved expansion-valve and the temperature of the air falling to 238° absolute. The expanded air then exhausts from the cylinder Q through 125 pipe R at a lower temperature than that of the cooling - chamber—namely, 238° absolute—into the surface condenser S. By the circulation of air by blowers U³ U⁴ through and from the tubes in the surface condenser the 130 temperature of the air is again raised during its passage from the pipe R through the condenser to the pipe T to the temperature 252° absolute. The air, having completed the cy-

- cle, is reduced to its initial pressure and temperature and is consequently ready to go through the same process again. It must be distinctly understood that the pressures and 5 temperatures given above are subject to alteration according to circumstances, the efficiency of the plant becoming greater as the range of temperature is reduced. The compressors and expanders are double-acting and 10 may be constructed of any suitable material, while the walls and covering or roofing of the cooling-chambers V V and the outer walls W W may be insulated with any suitable non-conductor.
- 15 I would also have it understood that I may employ any suitable fluid in lieu of air, as hereinbefore referred to, to fulfil the functions of the working medium—*i. e.*, the medium employed in the closed cycle which is 20 to be compressed, cooled, and expanded, as aforesaid.
- Having now particularly described and ascertained the nature of my said invention and in what manner the same is to be performed, 25 I declare that what I claim is—
- The combination substantially as described

in a cooling and refrigerating apparatus, of the two engines G' and C', the compression-cylinder C and expansion-cylinder Q in line with engine C' and connected therewith, the 30 compression-cylinder G and expansion-cylinder M in line with engine G' and connected therewith, the tank E³, the condensers E and K located in said tank, pipe D connecting compression-cylinder C and condenser E, pipe 35 F connecting condenser E and cylinder G, pipe H connecting cylinder G with condenser K, pipe L connecting condenser K with expansion-cylinder M, a refrigerating-chamber, two coolers O and S located therein, a pipe N 40 connecting the cooler O with expansion-cylinder M, the pipe P connecting the cooler O and the cylinder Q and the pipe R connecting cylinder Q with the cooler S, and a pipe T connecting the cooler S with the compression-cylinder C, as and for the purposes set forth.

Signed this 6th day of May, 1895.
BERNHARD ALEXANDER SMITH.
